UNITED STATES PATENT OFFICE.

WILLIAM KENT KISE, OF KANSAS CITY, MISSOURI, ASSIGNOR TO THE EVERBRITE STOVE COMPANY, OF KANSAS CITY, MISSOURI, A CORPORATION OF MISSOURI.

OIL BURNER.

Application filed March 16, 1925. Serial No. 15,778.

To all whom it may concern:

Be it known that I, WILLIAM KENT KISE, a citizen of the United States, residing at Kansas City, in the county of Jackson and

5 State of Missouri, have invented certain new and useful Improvements in Oil Burners; and I do declare the following to be a full, clear, and exact description of the invention, such as will enable others skilled in the art 10 to which it appertains to make and use the same, reference being had to the accompanying drawings, and to the figures of reference marked thereon, which form a part of this application.

15 This invention relates to oil burners and particularly to oil burners for domestic heaters.

The primary object of the invention is to 20 provide a simplified, inexpensive, efficient oil burner whereby hydrocarbon distillates can be converted into vapor or gasified to combine with air to form a combustible mixture.

It is also the purpose of the invention to 25 provide means whereby the outlet for the vaporizing chamber can be closed off in a convenient manner to prevent vapor from passing into the distributing chamber of the burner and finally seeping out into the room 30 when the supply of oil to the burner is cut off. Ordinarily, oil burning domestic heaters employ a needle valve in the supply pipe, which feeds oil to the vaporizing chamber, the vaporization being the result of heat. 35 When it is desired to discontinue the burner, the needle valve is closed but since the vaporizing chamber is still hot, the trapped oil will continue to vaporize for a short time but the period of time is long enough to permit 40 enough oil to vaporize and pass out through the distributing chamber unignited into the room. The result is that an objectionable odor permeates the room and for this reason the domestic heaters have been 45 considered more or less objectionable.

I employ a valve for supplying oil to the vaporizing chamber and preferably I use a needle valve, but in addition to this, I provide a valve at the outlet for the vaporizing chamber, that is, between the vaporizing zone 50 and the distributing chamber or mixing chamber of the burner. Therefore, when the supply of oil is turned off, I can also close the discharge end of the vaporizing chamber so that any generated vapor is trapped be-

tween the two valves and as soon as the vaporizing chamber cools down, the vapors will condense down to oil. This entirely eliminates the objection above enumerated.

The closing-off valve for the vaporizing 60 chamber is of novel construction and I prefer to employ it together with the burner casting herein illustrated to provide a complete unit.

The novel construction of the invention 65 will be apparent by reference to the following description in connection with the accompanying drawings, in which—

Fig. 1 is a perspective view of a complete 70 burner unit.

Fig. 2 is a cross sectional view through the mixing chamber and the distributing chamber on line 2—2 of Fig. 1.

Fig. 3 is a detail perspective view of one 75 of the disks having orifices through which the combustible mixture passes to be ignited.

Fig. 4 is a cross sectional view through the vaporizing chamber of the burner and through the distributing chamber of the burner on line 4—4 of Fig. 1. 80

Fig. 5 is a perspective view partly in section of the closing off valve, and

Fig. 6 is a vertical, longitudinal, sectional view through the closing-off valve, the valve element and stem being shown in elevation. 85

The main part of the burner consists of a hollow casting 1, substantially in the form of a rectangular tube or box closed at its respective ends and having openings 2 in the top wall 3 thereof, the openings receiving perforated disks 4 through which the mixture passes to be ignited. The distributing chamber is closed except for the top openings and an inlet opening 5, which constitutes the discharge end of a tubular mixing chamber 6. The tubular mixing chamber has one end distant from its discharge closed, as by a wall 7. The wall 7 has an opening 8 to receive a vapor pipe 9 leading from the vapor generator. The side of the mixing chamber is provided with an air inlet port 10, at the edges of which are guides 11 and 12 to receive a sliding screen frame 13, having a rectangular panel or screen 14 adapted to be moved on the guides to open and close the opening 10. 90

The front wall 15 of the casting is provided with a lateral shelf or pan 16, having a groove 17 to receive oil whereby the vaporizing chamber can be primed. The pan or 110

shelf is provided with longitudinal openings 17' to admit air from the bottom thereof and just above the slots or openings 17' are vapor distributing tips or disks 18, inclined in the 5 annular seats 19 above the floors of the recesses 20, which communicate with the space in the casting 1 through the medium of openings 21, spaced above the floors of the recesses 20 and above the floor of the hollow 10 casting 1.

The vapor generator is shown as comprising a tube 22 in line with the flame which issues from the disks 18 and also above the groove 17 so that it can be heated from either 15 source.

At the inlet end of the vaporizing chamber 22 is a needle controlling valve 24, which will control the supply of oil to the vaporizing chamber 22. The vaporizing chamber 20 may be supported at one end by the bracket 25, the opposite end of the vaporizing chamber being held by the wall 7, as clearly indicated in Fig. 1.

At the end of the vaporizing chamber is 25 a valve. The valve is in a casing 26 having a vertical orifice 27 in which is a rotatable stem 28, passing through a packing gland 29. The packing consists of rings, one of 30 which has a lower edge wedge-shaped in cross section, as indicated at 30, to fit in a corresponding groove 31 in the valve casing. The upper edge of the ring is inclined from each side to the center to provide a knife-ridge 32 to abut against the flat face 33 of 35 the upper ring 34. The upper ring has its upper face inclined toward the center from opposite sides to form a knife-contacting ridge 35 to engage the cap 36 so that when the cap is screwed onto the collar 37, the 40 packing will be made tight, yet the valve stem 28 can rotate. The valve stem is adapted to be rotated by a tool which may engage the head 38 and at the lower end of the valve stem is an offset or eccentric crank 45 pin 39, which engages a hole 40 in a reciprocating cylindrical valve 41, at one end of which is a cone 42 to engage the valve seat 43 to vary the effective port area of the discharge end of the vaporizer. The valve 41 50 is provided with longitudinal grooves 44 for the passage of vapor into the mixing chamber. By turning the valve stem 28, the cone 42 on the valve member 41 can be moved into and out of contact with the seat to vary the effective port area in an efficient way. The valve is tight and its construction is 55 such that leakage will be prevented.

The special advantage of the valve in the 60 casing 26 is to cut off the unconsumed vapor when it is desired to discontinue the operation of the burner. The operation of the device would be as follows:

Suppose it is desired to put the burner into operation. The oil is turned on

through the needle valve 24. The vaporizer is primed so that the oil will be converted into vapor. The valve in the casing 26 will be open to admit the vapor into the mixing chamber where it will mix with air entering through the opening 10 so that it can be ignited from the disks 4 and also from the disks 18. As soon as the priming has taken place, there will be enough vapor issuing through the ports 21 to maintain the vaporizer at sufficient temperature to vaporize the oil. The vaporizer may have a suitable packer or filtering medium in it, if desired. The orifice or opening 10 will be normally closed by the screen to prevent the priming fluid from igniting the mixture through the opening. The screen may also vary the effective port area of the air opening.

As soon as the device is functioning the valve in 26 will be open. When it is desired to discontinue the operation of the burner, the valve in 24 will first be closed, then the valve in 26 will be closed; therefore, the unburnt vaporized fuel will be trapped in the vaporizer and as soon as the vaporizer cools, the vapor will be condensed. This will prevent the unvaporized oil from passing out to the atmosphere, causing the objectionable odor frequently observed when the supply of oil to the burners has been cut off.

It will be seen that the invention is simple, rugged and adapted for operation so that liability of its getting out of order will be reduced to a minimum.

What I claim and desire to secure by Letters-Patent is:

1. An oil burner comprising an elongated, chambered body having burner openings in its top and a lateral shelf having a longitudinal trough and air slots between the trough and the chambered body, the body having inclined recesses communicating with its chamber, a generating tube located above the shelf and in the line of discharge from said recesses, a mixing chamber communicating with the generating tube and with the body chamber, and means for controlling intake to the mixing chamber.

2. In an oil burner, a casting comprising a chambered body having top burner openings and a shelf having an inclined rear wall provided with recesses having communication with the body chamber, the shelf comprising a trough and having air slots between the trough and said recesses, a generator tube above the shelf and in line of discharge from said recesses, a mixing chamber in communication with the generator tube and with the body chamber, and means for controlling flow to the mixing chamber.

In testimony whereof I affix my signature.

WILLIAM KENT KISE.
